UNITED STATES PATENT OFFICE

171,538

MEDICAMENT DISPENSER

Irvin J. Gershen, Hillside, N. J., assignor to Joseph Oshman and Solomon Oshman, New York, N. Y.

Application March 12, 1953, Serial No. 24,005

Term of patent 14 years

(Cl. D83—1)

To all whom it may concern:

Be it known that I, Irvin J. Gershen, a citizen of the United States, residing in Hillside, Union County, New Jersey, have invented a new, original, and ornamental Design for a Medicament Dispenser, of which the following is a specification; reference being had to the accompanying drawing, forming a part hereof.

Fig. 1 is a perspective view of medicament dispenser embodying my new design,

Fig. 2 is a side elevational view thereof,

Fig. 3 is an end elevational view thereof, and

Fig. 4 is a top plan view thereof.

I claim:

The ornamental design for a medicament dispenser, as shown.

IRVIN J. GERSHEN.
